UNITED STATES PATENT OFFICE

146,342

DESIGN FOR A COMBINATION MEASURING INSTRUMENT

Paul W. White, New Haven, Conn.

Application January 11, 1946, Serial No. 125,485

Term of patent 14 years

(Cl. D52—1)

To all whom it may concern:

Be it known that I, Paul W. White, a citizen of the United States, residing at New Haven, in the county of New Haven and State of Connecticut, have invented a new, original, and ornamental Design for a Combination Measuring Instrument, of which the following is a specification, reference being had to the accompanying drawing, forming a part thereof, in which:

Fig. 1 is an elevational front view of a combination measuring instrument embodying my new design; and

Fig. 2 is an end elevational view thereof.

I claim:

The ornamental design for a combination measuring instrument, substantially as shown.

PAUL W. WHITE.
